ATTORNEYS.

UNITED STATES PATENT OFFICE.

EUGENE A. CROWE, OF BROOKLYN, NEW YORK, ASSIGNOR TO THE E. S. HIGGINS CARPET COMPANY, OF NEW YORK, N. Y.

DESIGN FOR CARPET.

SPECIFICATION forming part of Design No. 28,279, dated February 8, 1898.

Application filed December 31, 1897. Serial No. 665,238. Term of patent 34 years.

To all whom it may concern:

Be it known that I, EUGENE A. CROWE, a citizen of the United States, residing at Brooklyn, in the county of Kings and State of New York, have invented and produced a new and original Design for Carpets, of which the following is a specification, reference being had to the accompanying drawing, forming part thereof, which represents a face view of a carpet in which my new design is embodied.

The invention relates to a design to be worked into or upon surfaces, such as carpets and similar fabrics; and it consists of the novel conformation of the figures, as herein shown and claimed.

The prominent feature of the design is a fanciful composite figure A, embodying a floral centerpiece, a border composed largely of palm scrolls of varying sizes, and leaf-scroll

decorations for the border. Near one end of the composite figure A the half-sections B and B' of another composite figure are drawn, the composite figure shown in two parts differing materially from the complete composite figure A only in the arrangement of the centerpiece, in which the character of the floral decoration is different. Near the opposite end of the complete composite figure A "repeats" C and C' of the border of the sectional composite figure are shown. Between the composite figures floral pieces are displayed.

I claim—

The design for carpet, substantially as shown.

EUGENE A. CROWE.
